(57) **CLAIM**

The ornamental design for a vehicle taillight as shown and described.

DESCRIPTION

FIG. 1 is a front top left perspective view of a vehicle taillight according to the new design.

FIG. 2 is a front view thereof.

FIG. 3 is a right-side view thereof.

FIG. 4 is a left-side view thereof.

FIG. 5 is a top view thereof; and,

FIG. 6 is a bottom view thereof.

The mirror image of the vehicle taillight is claimed but not shown.

The light gray portions of the vehicle taillight form no part of the claimed design.

1 Claim, 6 Drawing Sheets
